UNITED STATES PATENT OFFICE.

JOHN G. TALMAGE, OF CLEVELAND, OHIO, ASSIGNOR TO HERMAN B. THURSTON, OF PITTSBURGH, PENNSYLVANIA.

LOW-WATER ALARM.

1,405,953.

Specification of Letters Patent. Patented Feb. 7, 1922.

Application filed June 11, 1920. Serial No. 388,128.

To all whom it may concern:

Be it known that I, JOHN G. TALMAGE, a citizen of the United States, residing at Cleveland, in the county of Cuyahoga and State of Ohio, have invented a certain new and useful Improvement in Low-Water Alarms, of which the following is a full, clear, and exact description, reference being had to the accompanying drawings.

- 10 My invention relates to low water alarms of the type wherein a fusible element normally closes a steam pipe leading to an alarm signal, the fusible member under sufficient increase in temperature melting and allowing the alarm to operate. One of the objects in my invention is to provide, in a low water alarm of the type which may be applied to the crown sheet of boilers and operate to sound a whistle upon the water falling 20 below a predetermined level, a positive closure for the steam line leading to said whistle so that under no conditions save that of excessive temperature may any steam escape.
- 25 A further object of the invention is to provide a socket member having a plug disposed therein with a bore normally filled with readily fusible material, the plug being threaded to the socket member by tapering 30 threads whereby a tight fit is assured, thereby allowing said plug to be removed and replaced repeatedly as desired, without causing liability of leaks.

A further object of the invention is to provide a device which is simple and can be cheaply made and which is highly efficient in use.

In the accompanying drawings, wherein my invention is illustrated, Fig. 1 is a side 40 elevation partly broken away showing a boiler equipped with my low water alarm; Fig. 2 is an elevation of the socket member, the internal threads being shown in dotted line position; Fig. 3 is a section on the line 45 3-3 of Fig. 2, the plugs being shown in position; Fig. 4 is a plan and elevation of the plug containing a fusible material and Fig. 5 is a plan and elevation of the closure for the bottom of the socket member.

50 Referring to the drawings, a boiler of any suitable type is shown at 1, the crown sheet being indicated at 5. A socket member 2 is shown as connected to a pipe 4, a whistle 6 being connected to said pipe as shown. The 55 socket member, generally indicated at 2,

comprises a hollow casing-like member indicated as provided with external tapered threads 8 whereby it may be threaded to the crown sheet of the boiler. A plug 9, which may have a wrench engaging portion 12, is 60 shown as closing one end of the socket member the two being shown as secured together by means of tapering threads 10. A chamber 11 is provided intermediate the ends of the socket, and communicating with this chamber 65 is a series of apertures 14, here shown as cruciform in arrangement, which afford communication with the exterior of the socket. A passage 16 is shown as extending from the chamber 11, which passage may 70 terminate in a tapering thread 17 to which steam pipe 4, Fig. 1 is shown to be threaded.

A plug 20 having a wrench engaging portion 21 is shown as closing the lower end of the channel 16, the plug being indicated as 75 provided with a tapering thread 22 to fit a similar thread in the wall of the casing 2. A tapering bore 24 is shown as provided in the plug 20 and within this bore the fusible material 26 is placed. It will be noted that 80 communication through the apertures 14, with the chamber 11 and channel 16 is open when the plug 20 is not in place. The latter, however, in position closes such communication and it is only after the fusible material 85 has melted that communication is opened.

The provision of tapering threads assures the tight fit of all connections at all times and does away with the difficulty experienced in former types of low water alarms which 90 were very apt to leak, especially if it is necessary to remove and replace the parts. By my invention the use of tapering threads insures tight joints and takes up any wear occasioned by the removing or replacement of the parts. 95

To renew the fusible element, the plug 9 may be removed from within the fire box; then the plug 20 may be unscrewed and a new plug carrying a fusible element readily inserted and caused to make a tight fit by 100 reason of the tapered thread 22; then the plug 9 is replaced.

In operation, when the water falls to a dangerous level the heat at the top of the crown sheet will be transmitted to the fusible material, which thus melts and flows from the plug 20, or will be blown out by the steam pressure, thereby opening communication between the boiler and the whistle, causing the latter to sound.

Having thus described my invention, I claim:

1. A hollow socket member having two internal threads, and having a chamber between said threads, an aperture extending through the wall of the socket member to said chamber, two aligned plugs, each engaging one thread, said chamber extending to said plugs, one of said plugs having a discharge opening and fusible material in said opening, said aperture communicating with the exterior of the member and with the interior of a boiler, and the other plug closing communication with the firebox.
2. A hollow socket member having two internal threads, and having a chamber between said threads and an aperture communicating with the interior of a boiler, said aperture extending through the wall of the socket member to said chamber, and two aligned plugs, each engaging one thread and forming a steamtight connection with the socket member, said chamber communicating with said plugs, one of said plugs having a discharge opening and fusible material in said opening.
3. A hollow socket member having two internal threads, and having a chamber between said threads, an aperture extending through the wall of the socket member to said chamber and two plugs, each engaging one thread, said chamber extending to said plugs, one of said plugs having a discharge opening and fusible material in said opening, said last mentioned plug being smaller than the other plug, said chamber having openings communicating with the exterior of the member and closed by the plugs respectively, one of said openings being large enough to allow passage of the largest plug whereby both plugs are removable through said opening.
4. A hollow socket member having two internal threads and having a chamber intermediate said threads, an aperture extending through the wall of the socket member to said chamber, two plugs, each engaging one thread, whereby said plugs serve to close said chamber a discharge conduit communicating with said chamber through a passageway in one of the plugs, and fusible means closing said passageway.
5. The combination of a tubular hollow socket member having a chamber intermediate its ends and apertures leading from said chamber to the external surface thereof, the ends of said socket member being provided with internal tapering threads, tapering threads adjacent the intermediate portion of said socket member, a plug having a central bore threaded to said last mentioned thread, fusible material in said bore with which said chamber communicates, and a plug threaded in the end of said socket member.
6. A hollow socket member having two internal tapering threads, having a chamber between said threads, an aperture extending through the wall of the socket member to said chamber, two plugs, each engaging one thread, one of said plugs having an aperture therein closed by fusible material, said plugs being of sufficiently different diameters to allow the smaller plug to be freely removed through the opening for the larger plug.
7. In combination with the crown sheet of a boiler, a hollow socket member secured to said crown sheet, a pipe leading from one end of said socket to a whistle, a plug secured to the other end of said socket member to close the same, whereby communication is closed between the chamber and fire box, a second plug threaded by tapering threads intermediate the ends of said socket and provided with a bore containing fusible material, said socket member having a chamber between said plugs, extending to them, and having an aperture leading from the external surface to the chamber and communicating with the interior of the boiler.
8. The combination of a tubular socket member, an aperture leading from the interior to the exterior thereof, the ends of said socket member being provided with internal tapering threads, tapering threads adjacent the intermediate portion of said socket member, a thermal plug threaded to said last mentioned threads and adapted to be affected by heat to open the passageway, and a plug threaded in one end of said socket member.
9. In combination, a socket member comprising a tubular body open at each end, internal threads adjacent one end of said tubular body, a central portion of said socket member being reduced in external diameter, and having tapering internal threads adjacent said reduced portion, all of said hereinbefore mentioned threads tapering one direction, a chamber between said threads having an opening extending laterally through the walls of the member and plugs engaging said threads respectively and closing the ends of said chamber.
10. In combination, a socket member comprising a tubular body open at each end, external and internal threads adjacent one end of said tubular body and adjacent each other, a central portion of said socket member being reduced in external and internal diameter, and having tapering internal threads adjacent said reduced portion, all of said hereinbefore mentioned threads tapering one direction, a chamber between said threads having a lateral opening through the walls of said member and plugs engaging said threads respectively to close the ends of said chamber.
11. A socket member comprising a tubular body, external and internal threads adjacent

one end of said tubular body and adjacent each other, a central portion of said socket member being reduced in external and internal diameter, and having tapering internal threads adjacent said reduced portion, all of said hereinbefore mentioned threads tapering one direction, the other end being further reduced in diameter and provided with internal threads tapering in a direction opposite to the taper of said first mentioned threads.

12. In combination with a crown sheet of

a boiler, a socket member comprising a tubular body portion having channels therein closed by two plugs, one channel leading to 15 a signal and the other leading to a fire box, one of said plugs being fusible, and an intermediate open channel communicating with the interior of the boiler and with the interior of said tubular body portion intermediate of the plugs.

In testimony whereof, I hereunto affix my signature.

JOHN G. TALMAGE.
